TYPOGRAPHICAL MACHINE

Lynne Collins, San Francisco, Calif., assignor to
Mergenthaler Linotype Company, a corpora-
tion of New York

Application October 11, 1935, Serial No. 44,490

5 Claims. (Cl. 199—43)

This invention relates to typographical com-
posing machines of the general organization repre-
sented in Letters Patent of the United States
No. 436,532 to O. Mergenthaler, wherein circu-
lating matrices are released from a magazine in
the order in which their characters are to appear
in print and then assembled in line, the com-
posed line transferred to the face of a mold, the
mold filled with molten metal to form a type
bar or slug, and the matrices thereafter returned
10 through a distributing mechanism to the maga-
zine from which they started.

In such machines, the distributing mechanism
comprises rotating screws and an actuating de-
vice therefor, the screws being adapted and ar-
ranged to convey the matrices along a grooved
rail or bar, from which they are released at the
proper points to return them to appropriate chan-
nels in the magazine. During the operation of
20 this mechanism, however, it sometimes happens
that the rotation of the screws is abnormally
resisted as, for example, by a matrix becoming
lodged in the entrance to the magazine channel,
and to avoid damage to the magazine channel as
25 well as to the matrices, it is now common prac-
tice to provide means such as those disclosed by
A. P. Paine in U. S. Patent No. 1,099,465 for lock-
ing the screws against further rotation when the
resistance thereto becomes abnormal; and to pre-
30 vent the screws and the delicately constructed
mechanism associated therewith from being sub-
jected to undue strain, it is also common practice
to employ an actuating device which is rendered
inoperative when the screws become locked. The
35 actuating device generally employed for this pur-
pose comprises a clutch, the driving and driven
members of which are maintained in frictional
engagement by a spring which is automatically
rendered inoperative when the screws become
40 locked as a result of their rotation being ab-
normally resisted.

In practice, however, it has been found that this
arrangement is not entirely satisfactory because
when the clutch is first assembled it is essential
45 that the strength of the spring is such that the
force exerted thereby be sufficient to maintain
the driving and driven members in frictional en-
gagement when the resistance to the rotation of
the screws is normal but insufficient to subject the
50 screws to destructive strains before the clutch is
rendered inoperative in the event the resistance
to their rotation becomes abnormal; and when
the spring is so constructed the clutch has a
tendency to slip after it has been in use and the
55 parts thereof subjected to wear.

The present invention is shown and described
as being an improvement on clutches of this type
to the extent that easily accessible and simply
constructed means are provided for adjusting
the spring so that the force exerted thereby be-
tween the driving and driven members of the
clutch may be maintained at substantially a de-
sired value, thus insuring a positive engagement
of these members when the resistance to the ro-
tation of the screws is normal and a disengage-
ment of these members the instant the resistance
to the rotation of the screws becomes abnormal.
Obviously, however, the principles involved are
capable of far broader application and may be
adapted to distinctly different types of distrib-
utors and the actuating devices therefor, and it
is to be understood that the present invention is
not limited to any specific form or embodiment,
except in so far as such limitations are specified
in the claims.

For a clear understanding of the invention,
reference may be made to the accompanying
drawing in which:

Fig. 1 is an elevational view of the end of the
distributing mechanism, partly broken away,
25 embodying the features of the present invention;
and

Fig. 2 is a sectional view taken along the line
2—2 of Fig. 1, and having portions thereof broken
away to more clearly show the relation of parts.

In operation, the matrices 10 are, as usual,
conveyed along a grooved bar or rail 11 by ro-
tating screws 12 and drop therefrom into their
proper channels 13 of a magazine entrance 14
which leads to a storage magazine (not shown).

As usual, certain of the screws 12 are provided
with disks 18, substantially similar to those dis-
closed in the above noted patent to A. P. Paine,
and as described in that patent they are pref-
erably formed with inclined or spiral flanges,
40 and are so arranged that in ordinary operation
they run freely in relation to each other, but with
their respective flanges or threads always in
lateral proximity so that if, for any reason, the
synchronism of the screws be interrupted, the 45
disks 18 will be shifted in angular relation to
each other, resulting in the lateral contact of
their respective flanges and consequently the
immediate and positive arrest or locking of the
screws; and to prevent damage the power which
drives the screws 12 is, as usual, supplied through
a friction clutch 15 which is adapted and ar-
ranged to be rendered inoperative when the
screws are so locked.

The clutch 15 comprises a driving disk 19 and 55

a driven disk 21. The driving disk 19 is rotatably mounted on a drive shaft 16 between two collars 23 and 24 which are so positioned as to prevent axial movement of the disk along the shaft, and, during a machine cycle of operation, it rotates continuously. The driven disk 21 is also rotatably mounted on the shaft 16 between collar 24 and a set screw 25 which are so spaced as to permit this disk to be moved axially along the shaft to carry a face member 22 mounted thereon into and out of engagement with the oppositely disposed face of the driving disk 19, and it is provided with a beveled offset dog member 26 adapted and arranged to interlock with a similarly shaped dog member 27 carried by a collar 28 fixedly secured, as by a pin 28a, to a sleeve 20. The sleeve 20 is so keyed to the drive shaft 16 as to be capable of being moved axially therealong under and against the influence of a compression spring 30 and it is resiliently coupled to the driven disk 21 by a torsion spring 29 which is secured at one end to a pin 31 carried by the collar 28 and at its other end to a similar pin 33 carried by the rear face of the driven disk. In setting the clutch the sleeve 20 is moved backwardly along the shaft 16 until the offset dog members 26 and 27 are in radial alignment at which time the torsion spring 29 is permitted to rotate the driven disk 21 with respect to the sleeve 20 until the dog members interlock, and when the dog members are so interlocked the compression spring 30 is permitted to force the sleeve 20 and the driven disk 21 forwardly along the shaft 16 until the face member 22 frictionally engages the oppositely disposed face of the driving disk 19 at which time the driving and driven disks, the sleeve and the drive shaft rotate as a unit.

As usual, the screws 12, are adapted and arranged to be rotated by the shaft 16 when the clutch 15 is engaged through a gearing arrangement 17 which comprises a gear 17a, mounted on the shaft in mesh with a gear 17b, mounted on one of the screws. The gear 17b is also in mesh with a gear 17c, mounted on another of the screws, and another gear 17d, which is also mounted on this second mentioned screw, is in mesh with a gear (not shown) mounted on the remaining third screw (not shown). As usual, the gearing arrangement is such that the screws rotate at the same rate of speed to convey the matrices 10 along the grooved bar or rail 11.

In the event, however, that the resistance to the rotation of the screws 12 is abnormally resisted and the shaft 16 becomes locked against further rotation by the interlocking action of the disks 18 in the manner set forth in the above noted patent to Paine, the driving disk 19, in continuing to rotate, pulls apart the interlocking dog members 26 and 27 against the action of the springs 29 and 30, and when the dog members are thus separated, the sleeve 20 moves axially along the shaft 16 under the influence of the compression spring 30 until a collar 36 mounted thereon abuts a bearing 37 in which the sleeve is mounted. The driven disk 21 being thus relieved of the influence of the compression spring 30 is instantly disengaged from the driving disk 19 and the latter continues to rotate idly.

From the above it is obvious that if the strength of the compression spring 30 is too small the clutch 15 will be inoperative, that is, it will slip even when the resistance to the rotation of the screws 12 is normal, and that if the strength of this spring is too great considerable damage

might be experienced before the interlocking dog members 26 and 27 would be pulled apart to render the clutch inoperative in case the resistance to the rotation of the screws became abnormal.

In accordance with the present embodiment of the invention means are provided for adjusting the compression spring 30 so that the pressure exerted thereby between the driving disk 19 and the face member 22 may be maintained at a value which is sufficient to hold them in frictional engagement while the resistance to the rotation of the screws is normal, but insufficient to prevent a separation of the dog members 26 and 27 the instant the resistance to the rotation of the screws 12 becomes abnormal; and to this end the housing 34 in which the compression spring 30 is positioned is closed at its outer end by a telescoping cup-shaped member 38 which when moved axially with respect to the sleeve 20 varies the compression in the spring 30. To permit the cup-shaped member to be so moved, it is provided with a stud 39, the outer end of which is secured in an opening formed in the base of the cup-shaped member as by a pin 40 and the inner end of which is threaded part way into a recess 41 formed in the rear end of the shaft 16. By turning the cup-shaped member 38 its position with respect to the sleeve 20 is varied and the compression in the spring 30 is varied accordingly; forward axial movement of the sleeve being prevented while the spring is being so adjusted by either the interlocked dog members 26 and 27 when the clutch is engaged or by the collar 36 abutting against the bearing 37 when the clutch is disengaged.

In further accordance with the present invention means are provided for locking the cup-shaped member 38 against further rotation after the desired compression has been obtained in the spring 30, and the locking means employed is such as to permit the re-setting of the clutch in the manner heretofore described, and to this end the collar 36 mounted on the sleeve 20 is provided with a set screw 42 having a reduced inner end 43 which, when the set screw is seated, extends through the sleeve 20 and into an elongated slot 44 in the cup-shaped member 38. To adjust the compression in the spring 30, the set screw 42 is backed off until the reduced inner end 43 is withdrawn from the elongated slot 44 and the cup-shaped member 38 is then turned through one or more complete turns to obtain the desired compression in the spring after which the set screw 42 is again advanced until the reduced inner end 43 is positioned in the elongated slot 44.

As previously stated, while the principles of the present invention may be and are advantageously employed in connection with a friction clutch, they may be similarly employed in connection with other type driving mechanisms where it may be desired to disconnect the driving force in the event of undue resistance of some driven part.

Having thus described my invention, I claim:

1. In a typographical machine, the combination of distributing mechanism, operating devices therefor including a main drive shaft having a driving disk, a driven disk and a sleeve mounted thereon, interlocking dog members carried by said driven disk and by said sleeve, resilient means for maintaining said dog members interlocked, resilient means for forcing said driven and driving disks into engagement, and means for so adjusting said last mentioned resilient means that

the forces exerted thereby are sufficient to maintain said driven and driving members in frictional engagement while the resistance to the operation of the mechanism is normal.

5. 2. In a typographical distributing mechanism having screws for conveying matrices along a distributor bar, the combination of a friction clutch, interlocking devices for effecting the automatic disengagement of the clutch, a spring acting through said devices for holding the clutch engaged, and means for varying the strength of the spring.

10. 3. In a typographical distributing mechanism having screws for conveying matrices along a distributor bar, the combination of a shaft for rotating the screws, interlocking devices for effecting the automatic disengagement of the clutch, a spring acting through said devices for holding the clutch engaged, and means for varying the strength of the spring.

15. 4. In a typographical distributing mechanism having screws for conveying matrices along a dis-

tributor bar, the combination of a shaft for rotating the screws, a sleeve mounted on the shaft, a friction clutch including driven and driving disks for rotating said sleeve and said shaft, interlocking dog members carried by said sleeve and by said driven disk, a spring acting through said members for maintaining the clutch closed, and means for varying the strength of the spring.

5. 5. In a typographical distributing mechanism having screws for conveying matrices along a distributor bar, the combination of a shaft for rotating the screws, a sleeve mounted on the shaft, a friction clutch including driven and driving disks for rotating said sleeve and said shaft, interlocking dog members carried by said sleeve and by said driven disk, a spring acting through said members for maintaining the clutch closed, means for varying the spring until its strength is at a desired value, and means for maintaining the strength of the spring at said desired value.
